WATCHMAKER'S POISING TOOL

Donald K. Wallace, Pensacola, Fla.

Application January 2, 1953, Serial No. 329,251

3 Claims. (Cl. 73—66)

This invention relates to watchmakers' implements, and more particularly to an improved tool for poising and aligning balance wheels.

A main object of invention is to provide a novel and improved watchmaker's poising tool suitable for use on a watchmaker's bench and being arranged to receive a balance wheel for rapidly and easily balancing the wheel so that it is accurately poised, the improved tool being simple in construction, being easy to adjust, and being provided with means for at times locking the balance wheel against rotation, whereby the balance wheel may be tried without the necessity of removing it from the poising tool.

A further object of the invention is to provide an improved watchmaker's poising tool which involves inexpensive parts, which is durable in construction, and which is arranged so that the entire operation involved in balancing a wheel may be accomplished without the necessity of removing the balance wheel from the tool.

Further objects and advantages of the invention will become apparent from the following description and claims, and from the accompanying drawings, wherein:

Figure 1 is a top plan view of an improved poising tool constructed in accordance with the present invention.

Figure 2 is an end elevational view of the poising tool, a portion of the tool being shown broken away to reveal detail construction.

Figure 3 is an enlarged cross sectional view taken vertically on the line 3—3 of Figure 1.

Figure 4 is a fragmentary transverse vertical cross sectional view taken on the line 4—4 of Figure 3.

Figure 5 is an enlarged horizontal cross sectional detail view taken on the line 5—5 of Figure 3.

Figure 6 is a top plan view of the movable jaw element 50 of the poising tool showing a modification thereof in accordance with the present invention.

Figure 7 is a cross sectional view taken on the line 7—7 of Figure 6.

Figure 8 is a cross sectional view taken on the line 55 8—8 of Figure 7.

Referring to the drawings, and more particularly to Figures 1 to 5, the poising tool is designated generally at 11 and comprises a base 12 of any suitable shape, the base being shown as hexagonal, merely by way of example. The base 12 is supported on a plurality of depending legs 13 which are formed at their top ends with threaded shanks 14 which threadedly engage in tapped bores 15 provided in the bottom of the base 12.

Designated at 16 is an upstanding arm which is rigidly secured on the base 12 adjacent an edge thereof, as by a plurality of screws 17 extending upwardly through bores provided therefor in the base 12 and threadedly engaging the bottom end of the arm 16. Base 12 is formed with an elongated slot 18 which terminates adjacent the arm 16 and which extends across a substantial portion of the width of base 12, as shown in Figure 1, said slot having

2

5 rotatably mounted therein a shaft 19 which extends longitudinally and centrally through the slot. One end of the shaft is reduced, as shown at 20, and is rotatably supported in a suitable recess formed therefor in the end of the slot, and the other end of the shaft is cylindrical, as shown at 21, and is journaled in the base 12 at the other end of the slot 18. Secured to the end of the shaft 19 adjacent the journaled cylindrical portion 21 is the external knob 22 which is employed for manually rotating the shaft 19. As shown in Figure 3, the shaft 19 is formed with external threads 23 which threadedly engage internal threads formed in the lower end portion of a second upstanding arm 24 slidably disposed in the slot 18; the lower portion of the upstanding arm 24 being in sliding engagement with the walls of the slot, as shown in Figure 4, and the arm being formed with the respective shoulders 25, 25 slidably supported on the top marginal surfaces adjacent the slot to support the arm 24 vertically.

20 Designated at 26 is a friction spring which is secured in a transversely extending position to the bottom of the arm 24, as by the bolts 27, 27 extending through the spring and threadedly engaged in the bottom portion of arm 24, as shown in Figure 4, the spring 26 projecting laterally beyond the slot 18 for a substantial distance on opposite sides and frictionally engaging the bottom surface of the base 12. Designated at 28 is a coiled spring which surrounds the portion of the shaft 19 adjacent the end 20 of said shaft, the spring 28 bearing at one end on the end of the slot 18 and at the other end on the arm 24, a recess 29 being provided in said arm to receive the end of the spring, as shown in Figure 3. Thus, the arm 24 is biased by the spring 28 to the right, as viewed in Figure 3, and the bottom spring 26 biases the arm 24 downwardly to bring the shoulders 25, 25 firmly into sliding engagement with the top surface portions of plate 12 adjacent the longitudinal margins of the slot 18. Thus, springs 28 and 26 combine to effectively prevent looseness or shaking of the movable upstanding arm 24.

30 Designated respectively at 30 and 31 are respective bearing retaining members secured to the top portions of the respective arms 16 and 24 in opposing relationship, the retaining members 30 and 31 being directed towards each other and being in alignment. As shown in Figure 3, each of the retaining members 30 and 31 is provided with a threaded shank 33 which is threadedly engaged in the top end of its associated arm 16 or 24, whereby the bearing retaining member may be readily removed to be replaced by another bearing retaining member of a different size or of a different shape, if so desired. As illustrated in Figure 5, each of the bearing retaining members is formed with an end recess 32 in which is secured a bearing 34 shaped to receive the pivot of a balance wheel.

35 Designated at 36 is a friction member which is secured horizontally to the top end of the upstanding arm 16; said friction member being formed with the rib 37 extending longitudinally thereof, the friction member 36 being adapted to be engaged by a vibrating tool 38 having a corrugated or ribbed surface, as shown in dotted view in Figure 2, whereby the arm 16 may be vibrated by moving the tool 38 longitudinally with its ribs or corrugations in contact with the rib 37 of the vibrating element 36.

40 In using the device, the balance wheel, shown, for example at 39 in Figure 1, is mounted with its pivots journalled in the respective bearings 34 of the bearing retaining members 30 and 31, the position of the upstanding arm 24 being adjusted by means of the knob 22 to provide the correct spacing between the bearings in the respective bearing retaining members 30 and 31 to properly support the balance wheel for free rotary movement. The balance wheel may then be vibrated by means of

the vibration, namely, by 37 with the the rib, causing and causing as above de tion down by shown at 41 adding or sub the wheel is rotating and thereof by n ment is mov above. In justed to co tate freely v agitation is ever, it will reached the
